Specification of Letters Patent. Patented Feb. 14, 1922.

Application filed December 3, 1921. Serial No. 519,655.

To all whom it may concern:

Be it known that we, EUGENE N. STROM and AXEL E. BLOMSTRAND, citizens of the United States, residing at Chicago, Cook County, Illinois, have invented a new and useful Improvement in Railway Crossings, of which the following is a specification.

Railway crossings involve, as a part of their construction, angularly disposed extensions at each corner of the crossing at which rail-sections forming the tracks in which the crossing is interposed, are secured, these extensions being provided with guard-portions for the flanges of the wheels 15 which incline inwardly relative to the opposed rail-engaging portions of the crossing from their outer ends toward the flange-groove intersections of the crossing. Where the conditions are such that the rails to be 20 assembled with the crossing may be inserted to position therein by lengthwise movement of the rails into the recesses provided in the crossing for their reception, the guard-portions of the crossing do not present any obstruction to such insertion, but where the 25 conditions are such that the rails must be connected with the crossing by movement of the rails vertically, as, for example, where two crossings are located relatively closely 30 together and single length rails connect such crossings, which occurs at double-track crossings, the crossings must be so constructed that the guard-portions will not prevent obstruction to thus assembling the 35 rails with the crossing.

Furthermore, it is recognized in practice that, to minimize danger of the wheels jumping the crossing, provision should be made for guarding the flanges of both 40 wheels of each set thereof throughout such portions of the crossing, that both wheels will be guarded at the intersection of the flange-grooves of the crossing.

One of our primary objects is to provide 45 a novel, simple and relatively inexpensive construction of crossing which will permit of the ready assembly therewith, and withdrawing therefrom, of the rail sections by movement thereof vertically, and which will 50 permit of the angularly disposed extensions thereof, and hereinbefore referred to, being provided of relatively short lengths, and

will require that only a relatively few devices, such as bolts, for securing the rails to the crossing, be provided.

55

Another of our primary objects is to provide in a crossing having the relatively short extensions referred to, regardless of the angle at which the flange-grooves of the crossing extend relative to each other, 60 means of a relatively inexpensive and simple construction, whereby the desired guarding surfaces for the flanges of the wheels, to insure the guarding of both wheels of a set thereof at the time of passing 65 over the intersection of flange-grooves in the crossing, are afforded.

It may be further stated in connection with the foregoing objects, that, particularly because of the character of metal required to be used, railway crossing structures are expensive to manufacture. It is therefore very desirable that the crossings be of such construction that the amount of metal required to be used in their production will be the minimum, it being possible by utilizing our invention to accomplish this purpose in the attainment of our objects, certain of which are those stated above.

Referring to the accompanying drawings—

Figure 1 is a plan view of a railway-crossing constructed in accordance with our invention, showing rails connected therewith. Figure 2 is an enlarged broken plan view 85 of one of the corner portions of the crossing of Fig. 1, showing the rails cooperating therewith, this being a view of the corner of the crossing at the lower left-hand portion of the crossing in Fig. 1. Figure 3 is 90 a section taken at the line 3 on Fig. 2 and viewed in the direction of the arrow. Figure 4 is a section taken at the line 4 on Fig. 2 and viewed in the direction of the arrow. Fig. 5 is a view like Fig. 4 with the filler block, rail and bolts omitted, and representing, by dotted lines, one of the positions assumed by the rail in either the assembling thereof with the crossing or the disassembling of the rail therefrom. Figure 6 is a view like Fig. 2 and of the parts of the structure therein shown, representing these parts in separated, yet related, positions, the bolts being omitted. Figure

7 is a view like Fig. 2 of another corner portion of the crossing of Fig. 1, the portion shown being the corner of the structure at the lower right-hand side of Fig. 1, 5 with a portion omitted. Figure 8 is a plan view of a combined filler and guard-rail portion forming a part of the structure shown in Fig. 7. Figure 9 is a plan view of a filler-block which cooperates with the 10 member shown in Fig. 8; and Fig. 10, a section taken at the line 10 on Fig. 7 and viewed in the direction of the arrow.

We have chosen to illustrate our invention as embodied in a crossing wherein the 15 flange-grooves intersect, at such an angle that our improvement, as regards the guard-rail extension feature, is applicable, in addition to the provision of means, in accordance with our invention, for adapting of the 20 insertion and withdrawal of the rails by vertical movement, but without intending thereby to limit our invention.

The particular illustrated construction of crossing comprises two hollow cast sections 25 11, two hollow cast sections 12 and four angular corner pieces comprising two similar sections 13 and two similar sections 14. The sections 11 and 12 are of the same construction but of different shape to correspond with the angularity of the flange-grooves to be provided in the crossing, and the sections 13 and 14 are also of the same construction but of different shape to correspond with said angularity of the flange-grooves. Each section 11 and 12 is formed as a straight hollow rail-section 15 and containing a longitudinal wheel-flange-groove 16 and having oblique faces 17 at their ends, and guard-rail sections 18 extend outwardly 30 correspondingly on the opposite ends of each rail-section 15 and contain wheel-flange grooves 19. The portions of the sections affording the guard-rail sections referred to are provided with outwardly projecting extensions 20 which are offset as shown relative to the portions of the guard-rail sections 18 with which the wheel-flanges engage, and thereby cause the outer ends of the sections 11 and 12 to present the recesses 21. To 35 construct a crossing with the four sections 11 and 12, these are assembled by bringing the oblique ends 17 thereof into meeting contact one with another, thereby producing a crossing of rhomboid form, as illustrated in Fig. 1, because of the inclination of these ends as shown in this figure, it being understood that where the crossing is to be of square form the ends 17 would extend at an angle of 45° to the median line of the 40 sections 11 and 12, respectively, or if of rhombus shape, other than that shown, the angles at which the ends 17 extend would be correspondingly varied.

The resultant formation referred to causes 45 the grooves 16 and 19 to be in proper align-

ment. With the parts assembled as described, angular braces 22, conforming to the inner corners of the crossing, are fitted into them between the heads and flanges, and against the webs, of adjacent rail-sections 15, and the assembled parts are bolted together, as by the bolts 22a. Into the acute angular space formed between each of two adjacent guard-rail sections 18 fits a correspondingly shaped corner piece 13 and into the other angular spaces, which are of obtuse form, fit the correspondingly shaped corner-pieces 14.

The inner surfaces of the outer ends of the corner pieces 13 and 14 are recessed as 80 represented at 23, these surfaces being so shaped, as shown more clearly in Fig. 5, as to conformingly fit the opposing surfaces of rails represented at 24, of the track for which the crossing is provided, applied laterally to position against these corner pieces to extend into the recesses 23, in which position the inner edges of the heads of the rails are in alignment with the portions 25 of the corner pieces 13 and 14, and forming 85 rail sections. Cooperating with the sides of the rails 24, opposite those sides engaging the corner pieces 13, are hollow filler blocks 26 which are preferably of wedge-shape as shown in Fig. 6, these blocks which 90 fit into the recesses 21, adjacent the corner pieces 13, being so shaped, each at one lateral surface, as to conformingly fit portions of the adjacent under sides of the heads of the rails 24 and portions of the upper surfaces of the adjacent rail flanges, and at 95 bosses 27 thereon, the adjacent sides of the rail-webs and portions of the under sides of the rail-heads and the upper surfaces of the rail flanges, as shown in Fig. 4. The filler 100 blocks 26 shown are so shaped at their upper surfaces as to cause them to form continuations of the guard-rail portions 18 of the sections 11 and 12, adjacent the corner pieces 13, in the particular illustrated embodiment 105 of our invention the outwardly flaring portions of these guard-rail portions and a straight portion thereof, the guard-rail portions of the filler blocks 26, being represented at 110 28, the portions 20 of the sections 11 and 12 being provided with inwardly projecting flanges 29 which are overlapped by the filler blocks 26 when the latter are assembled with the other parts of the structure hereinafter 115 explained.

Cooperating with the sides of the rails 24, opposite the sides thereof which engage the corner pieces 14, are hollow filler blocks 30 which are preferably of wedge shape as shown in Fig. 8, these blocks which fit within certain of the recesses 21, being each shaped at the lateral surface thereof which opposes the rail 24, as explained of the filler blocks 26. The upper portions of the filler blocks 30 are so shaped as to form, through- 120 125 130

out a portion only of their length, straight continuations 31 of the guard-rail portions 18 of the sections 11 and 12 adjacent the corner sections 14, the outer end portions 5 of the blocks 30 being of reduced height and so shaped as to conformingly fit the adjacent side surfaces of guard-rail sections 32, the outer ends of which flare outwardly as represented, these sections 32 forming 10 continuations of the guard portions 31. Additional filler blocks, represented at 33, shown as of wedge shape and containing in their upper surface grooves 34, fit between the flaring portions of the guard-rail sections 32 and the adjacent rails 24.

In the assembling of the rails 24 with the crossing the rails are lowered through vertical planes into the spaces provided between the outer ends of the corner pieces 13 20 and 14 and in the outer ends of the sections 11 and 12, the filler blocks 26 and 30 not being in place, and the spaces just referred to being preferably wider than the flanges of the rails 24, and the rails then shifted 25 laterally to cause the flanges at one side thereof to extend into the position as shown in lines in Fig. 4, as to the rail therein shown, the dotted representation in Fig. 5 showing a position assumed by the rail as 30 it is being lowered to seating position. The filler blocks 26 and 30 are then inserted endwise into the recesses 21 and against the adjacent faces of the rails 24 to the position shown in Figs. 1, 2, 4, 7 and 10 and the parts 35 thus assembled secured together by bolts represented at 35 and 36, the bolts 35 passing through openings in the ends of the corner pieces 13 and 14 and the guard-rail-forming portions of the sections 11 and 12, 40 and the bolts 36 passing through openings in the ends of the corner pieces 13 and 14, the extensions 20 of the sections 11 and 12, the webs of the rails 24 and the filler blocks 26 and 30, respectively. The guard-rails 45 32 are then positioned against the sides of the filler blocks 30 at the outer ends of the latter and the fillers 33 applied to position, and these parts secured together by bolts 37 and 38, the bolts 37 passing through openings in the guard-rails 32, the outer ends 50 of the blocks 30 and the webs of the adjacent rails 24, and the bolts 38 passing through openings in the outer ends of the guard-rails 32, the fillers 33 and the webs of the adjacent rails 24.

It will be apparent from the foregoing that by providing as parts of the filler blocks 26, guard-rail portions which are removable therewith from the crossing structure the ends of the sections 11 and 12 projecting beyond the flange-groove intersections and the sides of the corner pieces 13 and 14 may be made relatively short and without impairing the strength of the structure, thereby requiring the minimum amount

only of metal to be used and the minimum number of fastening devices. Furthermore, this feature of the invention, when used in combination with the guard-rails 32, permits of the manufacturing of the crossing 70 with relatively short ends extending beyond the flange-groove intersections, thereby minimizing expense, where the angle at which the flange-grooves intersect is such that extended guard surfaces are necessary to insure the proper guarding of the wheels before either strikes a groove intersection. In this connection, it may be stated that in practice the crossings would probably be made with the ends thereof extending 75 beyond the flange-groove intersections of such length that in those cases where the grooves intersect each other at less than a 60° angle, the extended guard surfaces referred to, and formed in the construction shown by the 80 portions 31 and 32, would be required to be used, though it is not our intention to limit our invention to this particular condition.

It will be observed that when it is desired to disassemble any one or more of the rails 24 from the crossing, the crossing proper is not in any way disturbed, it being necessary only that the bolts 36 and the filler blocks 26 be removed and where the extended guard surfaces 32 are provided the bolts 37 and 38 95 and filler blocks 33 also removed. With these parts removed, the rails 24 may be lifted vertically from their position within the confines of the railway crossing proper, and new rails substituted, as hereinbefore described, this feature of the invention being of particular value where two crossings extend relatively closely to each other and are connected together by single rail sections, the conditions presented preventing shifting of 100 the rails lengthwise in the assembly thereof with the crossing proper.

It will also be noted that by our improvements the engagement of the lateral surfaces of the ends of the corner pieces 13 and 14 and the lateral surfaces of the filler blocks 26 and 30, with the opposite sides of the rails 24, is over relatively large areas of the rails producing broad bearing surfaces and serving very effectually to resist stresses in operation.

Where the flange-grooves of the crossing intersect each other at an angle of 90° , or at such a lesser angle as above suggested, more than 60° , a filler block 26 would be provided for each rail, such extended guard rail portions not being necessary under such conditions.

While we have illustrated and described a particular construction embodying our invention, we do not wish to be understood as intending to limit it thereto, as the same may be variously modified and altered without departing from the spirit of our invention.

What we claim as new, and desire to secure by Letters Patent, is:

1. A railway crossing provided at a corner thereof with a portion extending outwardly beyond the flange-groove-intersection of the crossing, said portion being recessed to receive an end of a rail, a removable and replaceable filler block in said recess extending adjacent a side of the rail and presenting a guard-rail portion spaced from the head of the rail, and means securing said parts together.
2. A railway crossing provided at a corner thereof with a portion extending outwardly beyond the flange-groove-intersection of the crossing and presenting a groove along its upper surface extending lengthwise of said portion and affording a track section and a guard-rail section, said portion being recessed to receive an end of a rail for alignment with said track section, a removable and replaceable filler block in said recess extending adjacent a side of the rail and presenting a guard-rail portion spaced from the head of the rail and aligning with said guard-rail section, and means securing said parts together.
3. A railway crossing provided at a corner thereof with a portion extending outwardly beyond the flange-groove-intersection of the crossing, said portion being recessed to receive an end of a rail, a removable and replaceable wedge-shaped filler block in said recess extending adjacent a side of the rail and presenting a guard-rail portion spaced from the head of the rail, and means securing said parts together.
4. A railway crossing provided at a corner thereof with a portion extending outwardly beyond the flange-groove-intersection of the crossing and presenting a groove along its upper surface extending lengthwise of said portion and affording a track section and a guard-rail section, said portion being recessed to receive an end of a rail for alignment with said track section, a removable and replaceable wedge-shaped filler block in said recess extending adjacent a side of the rail and presenting a guard-rail portion spaced from the head of the rail and aligning with said guard-rail section, and means securing said parts together.
5. A railway crossing provided at a corner thereof with a portion extending outwardly beyond the flange-groove-intersection of the crossing and presenting a groove along its upper surface extending lengthwise of said portion and affording a track section and a guard-rail section, said portion being recessed to receive an end of a rail for alignment with said track section, a removable and replaceable filler block in said recess extending adjacent a side of the rail and presenting an outwardly flaring guard-rail portion spaced from the head of the rail and aligning with said guard-rail section, and means securing said parts together.
6. A railway crossing provided at a corner thereof with a portion extending outwardly beyond the flange-groove-intersection of the crossing and presenting a groove along its upper surface extending lengthwise of said portion and affording a track section and a guard-rail section, said portion being recessed to receive an end of a rail for alignment with said track section, a removable and replaceable wedge-shaped filler block in said recess extending adjacent a side of the rail and presenting an outwardly flaring guard-rail portion spaced from the head of the rail and aligning at one end with said guard-rail section, and means securing said parts together.
7. A railway crossing comprising a structure presenting rail sections arranged in intersecting relation and having portions which extend outwardly beyond the track-section-intersections of said structure at the corners of the latter, members located in the angles at the corners of the structure formed by the outwardly-extending portions thereof, the structure presenting recesses at the corners of the structure between said portions and members to receive the ends of rails, removable and replaceable filler blocks located in said recesses adjacent sides of said rails and presenting guard-rail portions, spaced from the heads of the rails, and means for securing said parts together.
8. A railway crossing comprising a structure presenting rail sections arranged in intersecting relation and having portions which extend outwardly beyond the track-section-intersections of said structure, at the corners of the latter, members located in the angles at the corners of the structure formed by the outwardly extending portions thereof, said outwardly extending portions presenting guard-rail sections and said members presenting track-sections aligning with the track-sections of said structure, the outer ends of said members being recessed to receive the ends of rails for alignment with the track-sections of said members, and the outwardly extending portions of said structure being recessed, and removable and replaceable filler blocks insertable into the recesses in said outwardly extending portions to extend adjacent the sides of the rails and presenting guard-rail portions spaced from the heads of adjacent rails and aligning with said guard-rail sections, and means securing said parts together.
9. A railway crossing provided at a corner thereof with a portion extending outwardly beyond the flange-groove-intersection of the crossing, said portion being formed of sections extending side by side and presenting a recessed portion to re-

70

ceive an end of a rail, a removable and replaceable filler block located in said recess and extending adjacent a side of the rail and presenting a guard-rail portion spaced from the head of the rail, and means securing said parts together.

25   11. A railway crossing provided at a corner thereof with a portion extending outwardly beyond the flange-groove-intersection of the crossing and presenting a groove along its upper surface extending lengthwise of said portion and affording a track-section and a guard-rail section, said portion being recessed to receive an end of a rail for aligning with said track-section, and a removable and replaceable filler block located in said recess to extend adjacent a side of the rail, and means securing said parts together, said recess adapting said rail-end to be inserted thereinto and withdrawn by vertical as distinguished from longitudinal movement thereof, the assembly affording vertically uninterrupted contact with each other of the rail's head, web and flange at one side of the rail and the adjacent surface of the filler-block, and of said parts on the opposite side of the rail and said portion.

12. A railway crossing provided at a corner thereof with a portion extending outwardly beyond the flange-groove-intersection of the crossing, said portion being recessed to receive an end of a rail, a removable and replaceable filler block in said recess extending adjacent a side of the rail and presenting a guard-rail portion spaced from the head of the rail, said block having an extension at its outer end, a guard-rail applied to said extension, and means securing said parts together.

13. A railway crossing provided at a corner thereof with a portion extending outwardly beyond the flange-groove-intersection of the crossing and presenting a groove along its upper surface extending lengthwise of said portion and affording a track section and a guard-rail section, said portion being recessed to receive an end of a

rail for alignment with said track section, a removable and replaceable filler block in said recess extending adjacent a side of the rail and presenting a guard-rail portion spaced from the head of the rail and aligning with said guard-rail section, said block having an extension at its outer end, a guard-rail applied to said extension, and means securing said parts together. 70

14. A railway crossing provided at a corner thereof with a portion extending outwardly beyond the flange-groove-intersection of the crossing, said portion being recessed to receive an end of a rail, a removable and replaceable wedge-shaped filler block in said recess extending adjacent a side of the rail and presenting a guard-rail portion spaced from the head of the rail, said block having an extension at its outer end, a guard-rail applied to said extension, and means securing said parts together. 75
80
85

15. A railway crossing provided at a corner thereof with a portion extending outwardly beyond the flange-groove-intersection of the crossing and presenting a groove along 90 its upper surface extending lengthwise of said portion and affording a track section and a guard-rail section, said portion being recessed to receive an end of a rail for alignment with said track section, a removable 95 and replaceable wedge-shaped filler block in said recess extending adjacent a side of the rail and presenting a guard-rail portion spaced from the head of the rail and aligning with said guard-rail section, said block 100 having an extension at its outer end, a guard-rail applied to said extension, and means securing said parts together.

16. A railway crossing provided at a corner thereof with a portion extending outwardly beyond the flange-groove-intersection of the crossing, said portion being recessed to receive an end of a rail, a removable and replaceable filler block in said recess extending adjacent a side of the rail and presenting a guard-rail portion spaced from the head of the rail, said block having an extension at its outer end, a guard-rail applied to said extension, a filler block interposed between said guard-rail and said rail, and means securing said parts together. 105 110 115

17. A railway crossing provided at a corner thereof with a portion extending outwardly beyond the flange-groove-intersection of the crossing and presenting a groove along 130 its upper surface extending lengthwise of said portion and affording a track section and a guard-rail section, said portion being recessed to receive an end of a rail for alignment with said track section, a removable and replaceable filler block in said recess extending adjacent a side of the rail and presenting a guard-rail portion spaced from the head of the rail and aligning with said guard-rail section, said block having an ex- 130

tension at its outer end, a guard-rail applied to said extension, a filler block interposed between said guard-rail and said rail, and means securing said parts together.

5 18. A filler block formed along its upper surface with a guard-rail-forming portion only on one side thereof.

19. A filler block formed along its upper surface with a guard-rail-forming portion only on one side thereof and having an inclined guard-surface. 10
